UNITED STATES PATENT OFFICE

171,045

SAFETY BELT BUCKLE

William M. Noe, South Pasadena, Calif.

Application February 18, 1952, Serial No. 18,565

Term of patent 14 years

(Cl. D17—1)

To all whom it may concern:

Be it known that I, William M. Noe, a citizen of the United States of America, residing at South Pasadena, in the county of Los Angeles, State of California, have invented a new, original, and ornamental Design for a Safety Belt Buckle, of which the following is a specification, reference being had to the accompanying drawing, forming a part thereof.

Figure 1 is a perspective view of a safety belt buckle, showing my new design.

Figure 2 is a front view thereof.

Figure 3 is an end view thereof as indicated by 3 in Figure 2.

Figure 4 is another end view thereof as indicated by 4 in Figure 2.

Figure 5 is a side view as indicated by 5 in Figure 2.

I claim:

The ornamental design for a safety belt buckle, substantially as shown.

WILLIAM M. NOE.
